UNITED STATES PATENT OFFICE.

HARRY BRIDGMAN SMITH, OF NEW YORK, N. Y.

METHOD OF APPLYING TOP OR BOTTOM COVER PAPER TO BOXES AND THE LIKE.

Application filed October 8, 1925. Serial No. 61,197.

My invention relates to a new and improved method of top or bottom papering box parts or similar articles.

In the production of covered boxes by commercial methods largely employed, the side walls of the box shell have cover paper applied to them by what is called a stripping operation, or in other ways. Projecting margins of the cover paper at the open side of the box are turned in and secured to inner side faces, and margins of the cover paper are also turned and pressed on the outer face of the box top or bottom as the case may be, forming a covered margin around the entire contour of this wall, which will hereafter be referred to as the box top for the sake of simplicity. This leaves the large central area of the top uncovered, and for many classes of boxes it is considered necessary also to cover this area of the box.

It has been customary to draw the top covering paper from a roller and over a glue roll, cut it and apply it to the box top surface at a proper point to insure that the topping paper will fully cover the shell surface with proper overlap upon the previously affixed margins of the side wall cover paper, but without any excess which would produce unsightly overlaps of the topping paper. To insure against such overlaps the topping sheet must be cut shorter than the length of the box top, to provide an appreciable margin. It has heretofore been a difficult matter to properly cut the cover paper for this purpose and these difficulties have made the process slow and expensive.

The general object of the present invention is to provide an improved method for applying the top or bottom cover paper, which may be carried out either with simple or rudimentary appliances or with partly or substantially completely automatic machines, so that operations are practically continuous, and the continuous cover web may be properly measured and applied to the box tops in the proper positions, and cut off in such a way that the necessary edge margins above referred to are preserved; or, in brief, so that the cover paper is properly measured and accurately applied without care or attention of the operator and very rapidly and economically, resulting in a large production of topped or bottomed boxes at low cost.

The characteristics and advantages of the

invention are fully set forth in the following detail description of a representative method embodying the invention, with reference to the accompanying explanatory drawing which also illustrates simple devices or mechanisms as representative of mechanisms which may be employed to facilitate the performance of the process. After considering this explanation, skilled persons will understand that many variations may be made within the principles of the invention, and I contemplate the employment of any such variations that are within the scope of the appended claims.

In the drawings:

Fig. 1 is a diagrammatic perspective view showing mechanism employed in the process, and also illustrating and explaining one of the process steps.

Figs. 2 to 5 inclusive illustrate successive process steps.

Fig. 6 is a perspective view of a completed, topped or bottomed box part.

A cover-reel or platen P is mounted to rotate on an axis indicated by the shaft or trunnions 1. The platen is relatively thin and its main faces are covered with pads 2 of felt or other suitable compressible material. The vertical dimension of the platen (transverse its rotative axis) is substantially less than that of the box forms later mentioned. The upper and lower platen edges are faced with metal strips 3 to co-operate with a cutter 4. Associated with the platen are pairs of box-side pressing and gripping members 5 and 6 of which has a face 7 adapted to grip and press or bend a box side wall, and hold the box part firmly on the platen. Suitable mechanism indicated at 10 is provided for advancing and retracting the grippers at the proper time.

The operation of covering the tops or bottoms of box parts, is hereafter referred to by way of example as a topping operation, since the cover paper is applied to the broad top surface of a shallow box part, such as B¹ or B², which is understood in the present instance to be the box top. The bottoming operation is the same and the mechanism may be the same with due allowance for variation in the depth of the box part.

The continuous web W of cover fabric or paper is drawn from a paper-roll R over any suitable gluing mechanism 15 by which the face of the web which is outward with

respect to the platen is properly coated with adhesive, as indicated by the stippled surface 16.

Box forms F^1 and F^2 are mounted at opposite sides of the platen axis. They are contoured to fit box parts of a given size such as B^1 and B^2 , and are arranged for reciprocating movement toward and from the platen and for this purpose may be mounted 10 on shafts or rods 20 and 21. One of the forms, such as F^2 also desirably has vertical movement when adjacent the platen, as indicated in Fig. 3. Certain opposite sides, conveniently the vertical sides of the 15 forms, are cut away to provide recesses 23.

Desirably the platen may be located over a carry-off belt 30 and a guide plate 31 may be provided to aid in properly directing the completed or "topped" box parts to the 20 belt, which carries them away to any convenient discharge point.

Fig. 6 shows a typical box part such as a box cover B^1 ; which might otherwise be a bottom section (with no difference except 25 for dimensions), comprising side walls 40, end walls 41 and top wall 42. The side and end walls and margins of the top adjacent the sides and ends are usually covered with a suitable cover fabric or paper by previous 30 operations, and a top covering sheet 43 is to be applied to overlap said margins, the cover paper being cut or dimensioned somewhat smaller all around than the box top, so as to prevent the possibility of overlapping 35 and also to show a neat "trimming edge" when an "edging" strip is used. In this way a completely covered or finished box part is provided. Of course, the box parts if not square, may be positioned with 40 the longer dimension either vertical or horizontal. In the present illustration, the long sides 40 are vertical.

The cover web W is, in this case, of a width equal to the width of the box top less 45 the margins 44, which are not to be covered in order to prevent any overlap, and for other reasons, above mentioned.

In beginning operations, a length of the cover web is drawn off from the roll R over 50 the gluer 15 and is conveniently directed forward the platen by a guide roll such as 17. The upward portion of the web is held against the platen face P^1 in any convenient way, while a box part B^1 applied to the form F^1 is brought against the cover paper in 55 properly registered position, so that the marginal clearances 44 are evenly spaced at the vertical sides of the box top. The form F^1 is so positioned vertically that the 60 top wall 41 of the box part is substantially above the upper edge of the platen and specifically this distance is one-half the width of the platen edge 3, plus the top clearance 45, which is to be provided for reasons 65 above stated. The other form F^2 is also

similarly positioned and dimensioned with respect to the platen, when in its normal, or vertically-centered location.

The pressing and gripping devices 5 are now advanced to engage vertical box walls 70 40, as shown in Fig. 2. The pressing parts 7 bend in these side walls somewhat, as clearly shown in that figure, to more firmly grip and hold the box part, and prevent slipping, and incidentally to eliminate outward bulge in the walls. Definite association is thus obtained of the first box part with a continuous cover web and of both of them with the platen. For simplicity of 75 explanation, reference to cutting and other operations at this point is omitted, since in fact these operations may be omitted with regard to the first box part in a run.

Form F^1 is now retracted and the platen is rotated one-half turn while the grippers 5 remain in active position. Thus, the box part is carried around with the platen and the cover paper is simultaneously pulled from the roll and glued. The box part above mentioned is now in the position of 90 the box B^2 , Fig. 1, and cover paper has been drawn over the upper edge 3 of the platen and also against the vertical face P^1 , as shown in Fig. 1. Grippers 6 are retracted ready for reception of another box part B^1 , 95 positioned on form F^1 , the identification of the box parts not being intended to refer to the identical boxes but to their positions in different stages of the process. The form is then advanced to place a new box B^1 in the 100 manner previously described, and directly thereafter, the cutter 4, which conveniently is a rotary blade to co-operate with the metal strip 3, is rolled over the face of the strip on its central line to the position of Fig. 2, and in doing so, the cover web is severed, leaving glued marginal portions 50 and 51 while 105 form extensions of the cover paper which has been adhesively applied to the tops of two box parts. These margins, by the natural resiliency of the paper spring up somewhat to approximately the positions shown 110 in Figs. 2 and 3, but will not at this time be applied or affixed to the box top surfaces.

Immediately after the advance of form F^1 , 115 the grippers 6 are advanced to grip and retain the box part B^1 as previously described. The form F^2 is advanced to enter the box part B^2 shortly after part B^1 is positioned by form F^1 . The two box parts are then held firmly against opposite sides of the platen. Form F^2 is then moved vertically 120 from the position of Fig. 2 or 2^a, usually first downward to pull the cover paper apart at the severing line in case a clean cut has not been made, and then to press the upper free cover margin 51 firmly on the box top near its upper edge margin. The form and box thus reach the position shown in solid 125 lines in Fig. 3. The form is then moved up- 130

ward to the position shown in dotted lines in Fig. 3, and in this movement the lower free margin 50 is smoothed and press upon the box top in the proper final position. During the described vertical movements of the form, the latter may be slightly retracted or its pressure relaxed, to avoid reverse friction on the recently affixed margins while the form is being returned toward normal or central position after the wiping operations. Finally the form and box are brought back to normal or centered position in relation to the platen. This completes the covering of the box at B². Form F² is withdrawn horizontally, and the presses and gripper elements 6 are withdrawn laterally, permitting the box part to drop upon the carry-off belt 30.

The guide plate or deflector 31 serves to properly direct the box part to the belt.

Form F¹ is withdrawn simultaneously with the withdrawal of form F²; the grippers 6 at the position of Fig. 1 remain in active position to retain the box part which has been positioned against the cover paper by form F¹ in contact with the paper and against the platen.

The platen is now revolved one-half turn as indicated in Fig. 5, while the attendant places a new box part on form F¹. In the rotation of the platen the cover paper is drawn over its edge 3 which is approaching uppermost position, as indicated in Fig. 5; at the completion of one-half turn of the platen all parts are in the position of Fig. 1, except that cutter 4 is in its left hand position free of the platen, instead of in the right hand position, as shown in Fig. 1. The forms are now simultaneously advanced; the grippers are advanced to side press and retain the box part carried by form F¹, the cutter is moved to the right to sever the cover paper at the midwidth of the platen edge 3, producing the flaps 50, 51; form F² is then moved first down to wipe and press down the flap 51, and then up to press the lower flap 50, produced by a previous cutting action, and further operations are continued indefinitely in the order above described.

The described or analogous methods provide for substantially continuous and rapid operations with minimum labor. Only one unskilled attendant is required to place the boxes on the form F¹, and all other operations may be automatically performed by suitable mechanism such as that described. The present drawings do not show a complete machine, since the mechanism is not a part of the present invention, but is disclosed and claimed in a separate application. The use of a platen which is shorter in the vertical direction (or direction of web movement) than the box part permits the web to be properly measured or drawn off in proper

lengths on one main platen face, with margin or flap portions produced by the cutting operation ready for application to marginal portions of the box top by the vertical form movements as above described, and with due allowance for the uncovered edge margins, as also fully explained above, without the difficulties heretofore experienced in properly measuring or cutting off cover paper for this purpose.

The proper linear movement or guiding of the web in relation to the box tops to insure the proper lateral placing of the paper and proper vertical margins 44 may be provided by lateral shifting of the roll of paper in relation to the platen, or vice-versa.

I claim:

1. A method of applying facing sheets to flat surfaces of articles, comprising applying the article faces adhesively to portions of the sheet with the articles in spaced relation so that an unattached intermediate sheet portion is provided of less length and the sum of the distances between the points of attachment and the adjacent ends of the articles, the sheet being bent between the applied articles to allow the stated article spacing, severing said intermediate sheet portions between the attachment points, and affixing the free sheet portions to the surfaces.

2. A method of facing flat surfaces of articles, comprising adhesively applying the faces of a plurality of articles to a continuous sheet with the articles in spaced relation and with the sheet disposed in such form that the combined length of the articles is in excess of the length of the applied sheet, and certain intermediate sheet portions are free from adjacent margins of the article faces, severing the sheet between adjacent articles, and applying the unattached sheet portions to the article faces.

3. A method of topping box parts and the like, comprising advancing a continuous web of topping material, bending the web, adhesively applying a box part to the web at one side of the bend, advancing the web and applied box part and producing another bend in the web, applying another box part to the web in a position similar to the point of application of the first named box part, leaving the web included in the bend between and free from the applied box parts, severing the web between the box parts, and applying unconnected portions of the web adhesively to the box surfaces.

4. A method of topping boxes and similar articles, comprising advancing a continuous web, bending the web so that adjacent portions are in different planes, applying a box top adhesively to the web at one side of the bend, advancing the web and applied box top and producing another bend, applying another box part to the web in position analogous to the application position of the first

- box top, severing the web transversely at the bend, and applying free web flaps so produced to the box tops to complete the covering thereof with provision of edge margins.
- 5 5. A method of covering box tops and similar articles, comprising intermittently advancing measured portions of a continuous web by co-operation with a revolute platen and producing a bend in the web, adhesively 10 attaching a box part to a portion of the web at one side of the bend, repeating the web advancing and bending operation, similarly applying another box part to the web, severing the web between applied box parts, and 15 applying free web margins so produced to the box faces.
6. A method of covering box tops and similar articles, comprising intermittently advancing measured portions of a continuous 20 web by co-operation with a revolute platen and producing a bend in the web, adhesively attaching a box part to a portion of the web carried by one face of the platen, advancing the platen web and attached box part with 25 production of another web bend, similarly applying another box part to the web, which is thereupon spaced from the properly attached box part by the portion of the web included in the last produced bend, severing 30 the bend web portion between the box parts, applying free web margins so produced to the box faces, and continuing operations indefinitely so that the advancing web is continued and successive topped box parts are 35 produced, each including a severed part of the web.
7. A method of covering box tops and similar articles, comprising advancing a continuous 40 web in co-operation with a rotary platen and bending a portion of the web about a portion of the platen, applying surfaces of successive box parts to the web in association with the platen at one side of the bend and with marginal portions of the box surfaces 45 free of the cover web adjacent the bends, severing the cover paper substantially at midwidth of the bend, and applying the severed web margins to marginal portions of the box surfaces.
- 50 8. A method of covering box tops and similar articles, comprising advancing a continuous web in co-operation with a rotary platen and bending a portion of the web about a portion of the platen, applying surfaces of successive box parts to the web in association with the platen at one side of the bend and with marginal portions of the box surfaces free of the cover web adjacent the bends, severing the cover paper substantially at 55 midwidth of the bend, and moving one of the box parts slidingly in relation to the platen to apply free marginal portions of the cover web to the box surfaces.
- 60 9. A method of topping boxes performed 65 in co-operation with a revolute platen hav- ing sides disposed in different planes with an intermediate portion for article spacing and web severing purposes, comprising advancing measured lengths of a continuous web upon the platen sides, applying box tops 70 adhesively to the web so disposed upon the platen sides with adjacent marginal portions of the box tops extending beyond the platen and free of an intermediate portion of the web disposed on said intermediate platen 75 surface, severing the intermediate portion of the web to produce unattached marginal portions, and applying said unattached portions to adjacent marginal surfaces of the box parts.
10. A method of topping boxes performed in co-operation with a revolute platen having sides disposed in different planes with an intermediate portion for article spacing and web severing purposes, comprising advancing measured lengths of a continuous web upon the platen sides, applying box tops 80 adhesively to the web so that the box tops are located at opposite sides of the platen with adjacent marginal portions of the box 85 tops extending beyond the platen and free of an intermediate portion of the web disposed on said intermediate platen surface, severing the intermediate portion of the web to produce unattached marginal portions, and applying said unattached portions to adjacent marginal surfaces of a box part by 90 movement of said box part in relation to the platen.
11. A method of topping boxes comprising 95 advancing a continuous web of material by rotation of a reel whereby connected lengths of the web are disposed successively on adjacent reel faces with an intermediate bent web portion, applying a box top to a web portion 100 overlying one of the reel faces, partly rotating the reel and carrying the attached box part with it in association with the web, applying another box part to the web in 105 position similar to the application position of the box part first mentioned, severing the web midway of its bent portion and intermediate the applied box parts, and applying separated web marginal portions thus produced to adjacent marginal surfaces of the 110 box parts.
12. A method of topping boxes comprising 115 advancing a continuous web of material by rotation of a reel whereby connected lengths of the web are disposed successively on adjacent reel faces with an intermediate bent web portion, applying a box top to a web portion 120 overlying one of the reel faces, partly rotating the reel and carrying the attached box part with it in association with the web, applying another box part to the web in position similar to the application position of the box part first mentioned, severing the web 125 midway of its bent portion and intermediate the applied box parts, and applying separated 130

web marginal portions thus produced to adjacent marginal surfaces of a box part by sliding movement of the box part in relation to the adjacent reel surface.

5 13. A method of topping boxes comprising advancing a continuous web of material by rotation of a reel whereby connected lengths of the web are disposed successively on adjacent reel faces with an intermediate bent web 10 portion, applying a box top to a web portion overlying one of the reel faces, partly rotating the reel and carrying the attached box part with it in association with the web, applying another box part to the web in position 15 similar to the application position of the box part first mentioned, severing the web midway of its bent portion and intermediate the applied box parts, applying separated web marginal portions thus produced to 20 adjacent marginal surfaces of the box parts, and repeating the operations indefinitely with the production at each part turn of the platen of a completed, topped, box part, and with maintenance of the continuous web for 25 successive application of box parts.

14. A method of topping boxes comprising advancing a continuous web of material by rotation of a reel whereby connected lengths of the web are disposed successively on adjacent reel faces with an intermediate bent web 30 portion, applying a box top to a web portion overlying one of the reel faces, partly rotating the reel and carrying the attached box part with it in association with the web, applying another box part to the web in position 35 similar to the application portion of the box part first mentioned, severing the web midway of its bent portion and intermediate the applied box parts, applying separated web marginal portions thus produced to adjacent marginal surfaces of a box part by sliding movement of the box part 40 in relation to the adjacent reel surface, and repeating the operations indefinitely with

the production at each part turn of the 45 platen of a completed, topped, box part, and with maintenance of the continuous web for successive application of box parts.

15. A method of topping box parts and the like, comprising advancing and applying adhesive to a continuous web, bending the web, applying a box part to the adhesive surface of the web at one side of the bend, applying another box part in a relatively similar location, severing the web intermediate the box parts, and applying unconnected portions of the web adhesively to the box surfaces. 50 55

16. A method of topping boxes and similar articles, comprising advancing and adhesively conditioning a continuous web, bending the web so that adjacent portions are in different planes, applying box tops to the web in spaced relation at one side of the bend, applying another box part in a relatively similar location, severing the web transversely substantially at the center of the bend, and applying separated web flaps so produced to box faces to complete the covering thereof, except for an edge margin. 60 65 70

17. A method of covering box tops and similar articles, comprising intermittently advancing measured portions of a continuous web by co-operation with a revoluble platen and producing a bend in the web, 75 applying adhesive to a surface of the web during advance anterior to the platen, attaching box parts to a portion of the web at one side of the bend, applying another box part in a relatively similar location, 80 severing the web between the box parts and substantially midway of the bent web portion, and applying free web margins so produced to the box faces. 85

Signed at New York in the county of New York and State of New York this 7th day of October, A. D. 1925.
